UNITED STATES PATENT OFFICE.

NAPOLEON O. MERO, OF RAYMOND, WASHINGTON.

BOILER.

Application filed November 25, 1925. Serial No. 71,317.

My invention relates to boilers for generating steam or for heating water.

Among the objects of my invention are: the provision of a boiler which most efficiently utilizes the heat values of the gases of combustion; the provision of a boiler having the advantages both of fire tube and of water tube boilers; the provision of a boiler which will be compact; the provision of a boiler which will be inexpensive to manufacture; and the provision in a boiler of means whereby the hot gases are caused to come into most intimate association with the shell of the boiler.

15 My invention comprises the novel parts and the novel combinations thereof shown in the accompanying drawings, described in the specification, and more particularly defined by the claim terminating the same.

20 In the accompanying drawings I have shown my invention in a form which is now preferred by me, it being understood that changes in the particular form of the boiler may be made within the scope of the appended claim.

Figure 1 is a vertical axial section through my boiler and through a furnace and flue construction which may be associated therewith;

25 Figure 2 is a horizontal section through the same on the line 2—2 of Figure 1.

The boiler is of a type which may be designated as vertical, and comprises essentially an outer shell 1 and an inner shell 2 spaced from the sides and top 10 of the outer shell to form an annular water leg 11 between the shells 1 and 2, and a water and steam drum 12 between the top 10 of the outer shell and the top 20 of the inner shell.

30 At their lower ends the shells 1 and 2 may be connected, as, for example, by connecting each of them to a footing ring 3. The means for securing the shells to the footing ring, stay-bolts, and like structural features, have not been illustrated inasmuch as such devices and the manner of their use are common in the art, and any such devices as are found suitable may be employed, and at any point where engineering practice has 35 shown them to be desirable.

By the construction described, there is provided an inner chamber 25 within the inner shell 2, this chamber extending upwardly into the interior of the outer shell 1 and being surrounded at the sides by the water leg 11 and surmounted at the top by

the drum 12. The boiler is set into a casing 4, but spaced from the walls thereof, to provide an annular combustion chamber 40 extending about the boiler. Thus the gases 60 originating from combustion of fuel in the furnace 41 pass into the chamber 40 and about the outside of the shell 1.

Communication between the chambers 40 and 25 is afforded by means of short fire 65 tubes 5 connecting the upper portions of these two chambers. As shown herein these tubes extend merely between the shells 1 and 2, thus extending merely through the water leg 11. The gases of combustion, after passing through these tubes 5, are finally permitted to pass to the stack 42 through a flue connection 24 at a lower portion of the chamber 25. As shown, this flue connection 24 is built into the casing 4 and comprises a hole opening to the bottom of the 70 chamber 25.

In order to obtain the fullest advantage of the circulation of the gases of combustion thus provided, I prefer that water tubes 6 be 80 employed. Preferably these are positioned within the chamber 25. They are so positioned as to straddle the fire tubes 5, that is, their upper ends are connected above the tubes 5 and their lower ends are connected 85 therebelow. As shown herein, these water tubes 6 are arranged in banks corresponding to the banks of fire tubes 5, the lower ends of the water tubes in each bank being connected to the inner shell 2, and their upper 90 ends being connected to the upper end 20 of the inner shell. By this arrangement, gases passing through the fire tube 5 must pass closely by the water tubes 6, which would be arranged in a manner most suitable to 95 afford intimate association of the gases therewith. Only after passing the tubes 6 can the gases from the fire tubes 5 reach the flue connection 24. In addition they have passed upward over the outer shell 1 and 100 downward over the inner shell 2.

A further advantage of the provision of the water tube 6 lies in the circulation thus afforded within the boiler itself, avoiding the collection of sediment either in the lower 105 portion of the water leg 11 or in the bottom of the drum 12.

It will be observed that the shell 1 within the combustion chamber 40 is inclined upwardly and outwardly. The hot gases from 110 the furnace 41 tend to rise directly upward. As they impinge on the shell 1, due to its

inclination, they will be forced outwardly, but due to their natural tendency to rise directly upward, they will at all times, while rising, remain in intimate association with the shell, and will thus be induced to impart a considerable degree of heat directly to the shell.

Likewise, the inner shell 2 is inclined similarly to the shell 1, but with its sides now converging toward the flue connection 24. This restricts the opening for the gases as they cool, and also by bringing the surface of the shell more nearly in the line of movement of the gases, insures more intimate contact of the hot gases with the shell.

As is usual in boilers, manholes 15, steam connections 16 and proper gauges, feed water supply connections, blow-off connections and the like, are provided, although the latter are not shown, their manner of use and connection being obvious.

What I claim as my invention is:

In a boiler, in combination with a casing enclosing a combustion chamber, an upright boiler shell within such combustion chamber and spaced from the side walls of the casing to afford free passage of gases therebetween; a second shell, extending within the bottom of the first shell, and spaced therefrom at its top and sides, fire tubes extending through the boiler and affording communication between upper portions of said combustion chamber and the inner chamber within said inner shell; that inner chamber having a flue connection to its lower portion, the top of the inner and outer shells being connected by a cylindrical man-hole and covers normally closing the upper and lower entrances thereinto.

Signed at Raymond, Pacific County, Washington, this 13th day of November, 1925.

NAPOLEON O. MERO.
